The ornamental design for a tablet computer, as shown and described.

DESCRIPTION

FIG. 1 is a front perspective view of a tablet computer, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another left-side view thereof, in which a stand part of the tablet computer is in a closed position; and,

FIG. 9 is a rear perspective view of a tablet computer of FIG. 1, in which a stand part of the tablet computer is in a closed position.

The broken lines shown in the drawings represent portions of the tablet computer that form no part of the claimed design. The shade lines in the figures show contour and not surface ornamentation.
